FIG. 2.

FIG. 3.

FIG. 4.

Inventor:

E. M. MAXWELL,

By W. J. Fitzgerald & Co.

Attorney.

UNITED STATES PATENT OFFICE.

ERASTUS M. MAXWELL, OF CARDINAL, VIRGINIA.

MERRY-GO-ROUND.

Application filed November 3, 1922. Serial No. 598,801.

To all whom it may concern:

Be it known that I, ERASTUS M. MAXWELL, a citizen of the United States, residing at Cardinal, in the county of Mathews and 5 State of Virginia, have invented certain new and useful Improvements in Merry-Go-Rounds; and I do hereby declare the following to be a full, clear, and exact description of the invention, such as will enable others skilled in the art to which it 10 appertains to make and use the same.

The present invention relates to merry-go-rounds or roundabouts, for the amusement of and enjoyment by children and for 15 their exercise, and this invention is an improvement over the mechanism disclosed in my Patent No. 1,435,648, granted November 14, 1922.

An object of the invention is the provision 20 of a carousal comprising a novel construction and assemblage of the component elements, to provide a substantial structure.

Another object is the provision of a novel 25 operating mechanism for actuating the turn-table in an efficient manner.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawings, wherein—

Figure 1 is a side elevation of the merry-go-round, portions being shown in section.

Fig. 2 is an enlarged vertical section 40 through the base, portions being shown in elevation.

Fig. 3 is an elevation of one of the objects or figures for the riders and the actuating device operated thereby.

Fig. 4 is a vertical section through one of 45 the boats.

The device comprises a central mast 7 mounted for rotation above a suitable foundation or support 8, and having its upper end journaled in a cap bearing 9 to which 50 the guy ropes or wires 10 are connected for holding the mast upright as well as the parts carried by the mast.

A turn-table hub 11 is provided with a 55 socket 12 to receive the lower end of the mast, and said hub has radial sockets 13 receiving the inner ends of the spokes or

radial beams 14 of the turn-table. A floor or deck 15 is secured on the spokes or beams 14, and the marginal portion of the turn-table is supported by tie wires or members 16 secured to the turn-table and converging upwardly and anchored to a ring 17 fitted on and supported by the mast 7. The wires or members 16 prevent the turn-table from being depressed at the margin thereof under 60 the weight of the riders.

The turn-table and mast are supported for free rotation by a step bearing. Thus, the hub 11 has a depending pivot stud 18 seated for rotation on the anti-frictional 70 balls 19 disposed in a ball cup 20 that is seated in the central portion of a horizontal disk 21. The mast and turn-table are thus supported for free rotation, and the upper end of the mast being journaled in the cap 75 bearing 9 will prevent the mast and turn-table from tilting, as well as holding the mast and turn-table down on the base.

The disk 21 constitutes a part of the base, and is seated on and supported by several 80 posts 22 which are in turn supported by a cylindrical ring 23 located below the disk 21. The ring 23 has a lower inturned flange 24 seating on the foundation or support 8, and said ring has an upper outturned flange 25. 85 The posts 22 have shoulders 26 seating on the flange 25 and said posts also extend within the ring 23 and seat on the lower flange 24. Stud bolts 27 engage the foundation or support 8 and extend upwardly through the 90 flange 24 and disk 21, within the posts 22, and nuts 28 are threaded on the upper terminals of said bolts and bear down on the disk 21 for clamping the disk 21 on the posts and said posts on the base ring 23.

The actuating mechanism for turning the turn-table includes rock shafts 29 offset relatively to the vertical planes of the beams 14 in a plane below said beams, and said shafts are journaled in hangers 30 rigidly secured 100 to said beams and extending at an angle downward, as seen in Figs. 3 and 4. Double arms 31 are secured to the inner ends of said shafts, and extend upwardly and downwardly across the edges of the disk 21 and flange 25, and pawls 32 and 33 are pivoted to the upper and lower ends of said arms, respectively. The disk 21 is provided on its upper surface near the edge thereof with an annular series of ratchet teeth 34, and the 105 flange 25 is provided on the lower surface thereof with the ratchet teeth 35. The pawls

32 rest by gravity on the ratchet teeth 34, and the pawls 33 have weights 36 swinging said pawls upwardly against the ratchet teeth 35, whereby the oscillation of the shafts 5 29 will, by the engagement of the pawls with the ratchet teeth, rotate the turn-table, the pawls advancing along the ratchet teeth by an alternate action, as will be apparent.

The accommodations for the riders are of 10 two kinds as shown. Thus, boats 37 are supported on the turn-table and have seats 38 for the occupants, and hand levers 39 are secured to the corresponding shafts 29 underneath the boats and extending upwardly 15 through slots 40 in the floor or deck 15, to be oscillated forward and backward by the occupants of the boats, so as to oscillate the shafts 29.

Rocking or oscillating supports 41 for the 20 riders are also provided, being in the form of horses or animals, as shown, on which the riders can sit astride. The supports or objects 41 are fulcrumed, as at 42, on posts 43 fitted in sockets 44 secured to the outer ends 25 of the corresponding beams 14. Arms 45 are secured to the outer ends of the corresponding shafts 29 and have links or rods 46 connected thereto which are pivoted at their upper ends, as at 47, to the objects 41, where- 30 by the rocking motion of said objects will oscillate the shafts 29.

The riders by oscillating the objects 41 and levers 39 can therefore oscillate the shafts 29 for imparting movement to the 35 turn-table.

Having thus described the invention, what is claimed as new is:—

1. A merry-go-round comprising a turn-table, means having sets of ratchet teeth, a rock shaft carried by the turn-table, a 40 double arm secured to the shaft, pawls carried by said double arm and engaging the ratchet teeth, and means for oscillating said shaft.

2. A merry-go-round comprising a base 45 having portions with ratchet teeth on their upper and lower surfaces, a turn-table mounted for rotation on said base, a shaft carried by the turn-table, a double arm secured to the shaft and extending across the 50 edges of said portions, pawls carried by said arm above and below said portions and engaging said ratchet teeth, and means for oscillating said shaft.

3. A merry-go-round comprising a base 55 having an outturned flange with ratchet teeth on the lower surface thereof, said base having a disk above said flange with ratchet teeth on the upper surface thereof, a turn-table mounted for rotation on said disk, a 60 shaft carried by the turn-table, a double arm secured to the shaft and extending across the edges of said disk and flange, pawls carried by said double arm and engaging said ratchet teeth above said disk 65 and below said flange, and means for oscillating said shaft.

In testimony whereof I have signed my name to this specification.

ERASTUS M. MAXWELL.
